UNITED STATES PATENT OFFICE.

ALFRED KENDAL TOULMIN SMITH AND PERCY GOOD, OF LONDON, ENGLAND.

ELECTROMAGNETIC POWER DEVICE.

1,123,411.

Specification of Letters Patent.

Patented Jan. 5, 1915.

Application filed April 29, 1911. Serial No. 624,212.

To all whom it may concern:

Be it known that we, ALFRED KENDAL TOULMIN SMITH and PERCY GOOD, subjects of the King of Great Britain, residing at 5 London, S. E., England, have invented certain new and useful Improvements in Electromagnetic Power Devices, of which the following is a specification, reference being had therein to the accompanying drawing.

10 This invention relates to electromagnetic power devices.

The chief object of the invention is to provide an electromagnetic power device giving a reciprocatory movement of long range 15 and preferably exerting a substantially uniform pull throughout the whole of its movement.

The electromagnetic power devices according to this invention are especially applicable for operating railway points or railway signal devices, brakes, stamp mills, and like apparatus but their application is not restricted thereto.

According to this invention the electromagnetic power device comprises a central core with a limb or limbs or other members of magnetic material arranged along its side or sides or surrounding it, and a reciprocator in the form of a coil or coils 20 movable on the core, said reciprocator being of less length than the air-gap in which it moves, and the air-gap which surrounds the reciprocator increasing gradually toward the free end of the core, there being 25 suitable magnetizing windings for the core or the core being permanently magnetized.

The invention will be more fully understood from the following description taken in connection with the accompanying drawings in which:

Figure 1 is a diagrammatic view of one form of electromagnetic power device constructed according to this invention. Fig. 2 is a perspective view of another form of device. Figs. 3, 4, 5, 6 and 7 are respectively diagrammatic views of other forms of the device. Fig. 8 is a sectional elevation of a device constructed according to this invention such as might be used in practice for operating railway points or signals. Fig. 9 is a section of the device shown in Fig. 8, taken on the line $x-x$ in Fig. 8, looking in the direction of the arrows x , and Figs. 10 and 11 are elevations on a reduced scale of 50 the device shown in Fig. 8, looking in the direction of the arrow y in Fig. 8, and show-

ing the movable part of the device in the two extreme positions which it can occupy.

Like letters indicate like parts throughout the drawings.

Referring to Fig. 1, the device comprises a central core A of magnetic material with two outwardly spreading limbs A' extending along its length on opposite sides of it, and a magnetizing winding B is fixed at 60 the position shown on the central core A. The central core A, the limbs A' and the magnetizing winding B together form the stator. A reciprocator coil C, is movable on the central core A.

The coils of the stator and reciprocator are supplied with current from the same or different sources. If they are supplied from the same source they may be connected in series or parallel. The reciprocator is 70 caused to move by altering the degree of energization on one or both of the windings. The reciprocator may be moved electromagnetically in both directions or it may be moved electromagnetically in one 75 direction, and by gravity or a spring in the other direction. If the stator and reciprocator windings are supplied with direct current, then, on changing the direction of flow of the current in either one of the coils, 80 the reciprocator coil tends to move in the direction opposite to that to which it has previously tended to move. Similar effects are obtained with alternating current by changing the relative direction of the flow 85 of the current in the reciprocator and magnetizing coils.

The reciprocator coil tends to move on the central core so as to alter the magnetic flux passing through it. For any position 90 of the reciprocator coil on the central core the force will vary according to the variation of magnetic flux along the central core and between the latter and the limbs on each side of it. In order to get a substantially uniform pull along the whole length 95 of movement of the reciprocator coil it is necessary that the air-gap should increase toward the free ends of the central core and limbs. Such an arrangement is diagrammatically illustrated in Fig. 1. In order to provide this uniform pull when a uniform current is flowing, it is necessary to provide a uniform magnetic field in the air gap between the central core and the outer member, because the pull depends on the action 100 between the magnetic field and the current 105 between the magnetic field and the current 110

in the reciprocating coil. When current is sent through the reciprocating coil the magnetic reaction produced tends to make the strength of the magnetic field in the air gap, near the closed end of the core weaker and tends to strengthen it near the free end. In order to correct for this we increase the reluctance of the magnetic circuit at the free end of the core and by suitably proportioning this reluctance we are able to obtain substantially the uniform field necessary to produce the uniform pull.

In the construction illustrated in Fig. 5 (hereinafter described) the above principle applies but the maximum reluctance in this core is required at the center which is the point at the greatest distance from either stator coil and is the portion which magnetically corresponds with the free end in the above case.

Referring to Fig. 2, a central core A^2 is fixed to the closed end of a hollow conical member A^3 , the other end of this member A^3 being open. The magnetizing coil B is fixed on the central core A^2 and a reciprocator coil C is movable on the core A^2 . The operation of the device is exactly similar to that described in connection with Fig. 1.

In Fig. 3, a device similar to that shown in Fig. 2, is illustrated, the stator and reciprocator coils being of such form that the latter can move over the former. This obviously gives a greater range of movement than in a construction where the reciprocator coil can only move up to the stator coil.

When employing a device according to this invention for such an operation as moving a signal it is only necessary to exert a relatively small force after the signal has been brought to rest in one position. For this reason a smaller current may be employed for holding-on purposes such as just referred to. To further decrease the amount of current consumed the reciprocator coil may be provided with a magnetic armature which comes close to or engages the free ends of the central core and the limb or limbs or surrounding member. This is illustrated diagrammatically in Fig. 4, where the reciprocator coil C has attached to it an armature D , by means of rods D' . When the reciprocator coil moves as close as possible up to the stator coil B the armature D , bridges the free ends of the central core A , and the limbs A' . To automatically diminish the current taken by the apparatus, an arrangement for automatically switching in a resistance in the circuit is provided. The resistance E , is arranged in the circuit of the stator coil B and reciprocator coil C which are shown connected in series, F representing the battery, and G the operating key. The switch arm H is pivoted at H' and normally is held by a spring H^2 in engagement with a contact so as to

short circuit the resistance E . As the reciprocator coil C moves up to the stator coil B a projection D^2 on the armature D engages the switch arm H , so as to throw the resistance E into the circuit of the stator and reciprocator coils, thereby diminishing the current taken by them.

Referring to Fig. 5, a central core A^4 is arranged with limbs or members A^5 connected to both of its ends. Two stator coils B are arranged at the two ends of the central core A^4 and the reciprocator coil C is movable between them. The stator and reciprocator coils can be so connected to sources of electric current that the reciprocator coil C is caused to move in either one or the other direction along the central core A^4 . In this form of our device the core tapers inwardly from both ends, toward the center as shown so as to have the air-gap wider at the middle than at the ends.

In Fig. 6, we have shown a modification of the device shown in Fig. 5, and in which the outer member A^6 tapers inwardly from the center to both ends this construction having the same effect as that shown in Fig. 5.

In the modification shown in Fig. 7, a central core A^6 is provided with two members A^7 arranged beside it but not connected to it by magnetic material. A stator winding B is arranged at the center of the core A^6 and two reciprocator coils C are arranged to move on the core A^6 . The stator and reciprocator windings may be supplied with current so that the reciprocator coils move in relatively the same or opposite directions at the same time. When the coils move in relatively opposite directions at the same time the device may be used where it is desirable or necessary to obtain such movement in the device to be operated.

Referring to Figs. 8, 9, 10 and 11, a device constructed according to this invention is shown such as might be used in practice for operating railway points or signals. Its general form is similar to that described above in connection with Fig. 2. It comprises a central cylindrical core A^8 surrounded by a member of substantially cylindrical form A^9 . At the base of the central core A^8 there is a circular flange or disk A^{10} which screws into the cylindrical member A^9 as shown. The device is bolted to any suitable base. The fixed coil B is arranged as shown, around the central core A^8 . A reciprocator coil C is provided which can move on the central core A^8 . Current from the source of supply is led to terminals J on the outside of the member A^9 . The terminals J are protected by a cover J' . In Fig. 8, only one terminal is shown, the other one being directly behind it. Two leads B' connect the two terminals J respectively to the stator coil B .

Reciprocator coil C is wound on a brass bobbin C', and the leads K to the coil are brought through tubes L which are screwed into the upper flange of the bobbin. The 5 leads K are flexible and are connected to the two terminals J respectively so that the stator and reciprocator coils are in parallel. The tubes L at their upper ends screw into a plate M. Screwed into the plate M are 10 two pillars M', to which is attached a plate M² by nuts. The plate M² has screwed into it a draw-hook N. The draw-hook N holds in position a casing O and between the top 15 of the casing and the plate M² is a conical block of wood O'. The plate M is provided with a hole at its center through which passes a rod M³. The rod M³ at its lower end screws into an armature P. A spiral spring M⁴ surrounds part of the rod M³ and 20 is retained between the plate M and the armature P. The upper end of the rod M³ is provided with a flange or washer M⁵ held in position by a nut M⁶. A spiral spring M⁷ is held in position by the flange M⁵ and the 25 plate M. The springs M⁴ and M⁷, acting in conjunction with the rod M³, form a flexible connection between the plate M and the armature P and also act as buffer springs between the reciprocator and the armature 30 P. The armature P has portions cut away at P' to regulate the force of attraction with which it is held on to the core A⁸ and member A⁹. It is also provided with holes P² through which the tubes L pass, these holes 35 being of sufficient diameter to permit of the armature P having a tipping movement relatively to the plate M. With this construction it is possible for the armature to take up a true position with relation to the 40 ends of the cores A⁸ and member A⁹, even if the plate M is tipped, for example by a side pull on the draw-hook N. The coils on the stator and reciprocator may be completely inclosed by, for example, brass so 45 as to be damp proof. The device may be filled with oil to produce a dash-pot action on the reciprocator. The gap between the central core A⁸ and the member A⁹ gradually increases toward the free end of the 50 core A⁸ for the purpose of obtaining uniformity of pull, as described in connection with Fig. 2.

With the construction described above the reciprocating coil or coils can move close

up to the stator so that practically the whole 55 of the lines of force set up by the stator coil pass through the reciprocating coils, thereby enabling the apparatus to be constructed with a very high efficiency.

We claim:

1. In an electro-magnetic power device, the combination with a central, normally magnetized, core, of a reciprocator consisting of a coil, formed without magnetic material, surrounding the core and movable 65 thereon and an external member composed of magnetic material, magnetically connected, at one end only, to the core and gradually flaring outwardly from the core and said core being magnetized independently of any magnetism produced by the reciprocator.

2. In an electro-magnetic power device, the combination with a central, normally magnetized, core, of a reciprocator consisting of a coil formed without magnetic material and surrounding the core member and an external member composed of magnetic material, said external member being magnetically connected to the core member, at 75 one end only, and extending outside the said reciprocator, one of said members being so formed as to produce an air-gap increasing gradually from a point adjacent the point of connection of said member, 80 and said core being magnetized independently of any magnetism produced by the reciprocator.

3. In an electro-magnetic power device, the combination with a central normally 90 magnetized core, and a reciprocator consisting of a coil formed without magnetic material surrounding the core and movable thereon, of a hollow conical member magnetically connected, at one end only, to one 95 end of the core and open at its other end and providing an air-gap, increasing gradually in size toward the open end of said member, and said core being magnetized independently of any magnetism produced by 100 the reciprocator.

In testimony whereof we affix our signature in presence of two witnesses.

ALFRED KENDAL TOULMIN SMITH.

PERCY GOOD.
